UNITED STATES PATENT OFFICE.

ADOLPH D. BULLERJAHN, OF CHICAGO, ILLINOIS.

SEALING APPARATUS FOR CARTONS.

Application filed June 17, 1927. Serial No. 199,478.

The apparatus of the present invention is designed for the purpose of applying a seal coating of wax or the like to the end of a carton or package while in transit on a conveyor, and without lifting or in any way manipulating the carton or interrupting the continuity of its travel during the sealing operation.

Heretofore it has been customary to wax seal packages containing crackers, confections, or the like, by immersing the ends of the package in a bath of melted wax or like composition, which method requires a considerable amount of manipulation and interrupts the continuity of the feeding of packages from the wrapping position to the final point of discharge, and the present invention is designed to avoid such methods and to pass the ends of the cartons through a flowing body of wax discharged from a weir in such a way as to completely seal the ends while in position to travel upon the conveyor. In particular, the invention relates to the means provided for regulating and controlling the flow of wax over the weir in order to cause a complete sealing of the end face and edges of the carton without any excessive discharge of wax upon the side faces of the carton where sealing is not required.

The various adjustments presently to be described are further provided in order to regulate the discharge of the wax with due regard to the extent of surface to be covered, the nature of the sealing medium employed, the thickness of the seal coating required, the speed of travel of the conveyor, and other like factors involved in a proper application of the seal coating.

Further details will appear from a description of the invention in conjunction with the accompanying drawings wherein—

Figure 1 is a perspective view of the sealing apparatus of the present invention with the position of a carton indicated in dotted lines;

Fig. 2 is a sectional elevation showing the discharging column of fluid, wax, or other sealing medium;

Fig. 3 is a diagram illustrating the relation of the sealing apparatus to the conveyor;

Fig. 4 is a detail showing one form of weir; and

Fig. 5 is a similar view showing an alternate form of weir.

The apparatus as a whole comprises a tank consisting in the form shown of end walls 10—10, a vertical rear wall 11, a front obliquely disposed wall 12 and a bottom 13. The tank, as shown, is mounted upon standards 14, although obviously it might be otherwise supported.

Below the tank is located a drain pan 15 which is supported in sloping relation between the standards 14, being provided for the purpose of catching the overflow of excess wax from the sealing, and returning it through a suitable pipe 16 which leads to a pump or the like, not shown, from which in turn leads a supply pipe 17 for discharging the hot melted wax into the top of the tank or reservoir. In order to maintain a proper level within the reservoir, an overflow pipe 18 is provided which opens downwardly into the pan 15 through the base 13 of the reservoir. Since it is desirable to provide means for closely regulating the overflow level to meet variations in the conditions encountered, the upper end of the pipe 18 has screw threaded thereonto a cap 19 provided with one or more inlet apertures 20 leading to the interior of the pipe 18, which cap is carried by the lower end of a stem 21 threaded through a boss 22 in such a way as to permit the vertical elevation of the cap to be adjusted to regulate the overflow point.

The main reservoir is located in proximity to an endless conveyor 23, which may be in the form of a chain conveyor as shown, or in any other suitable form, although it is desirable to permit of a limited degree of lateral tilting of the conveyor to bring its surface into slightly oblique relation with respect to the horizontal floor level for a reason to be presently explained. As shown, the supporting surface of the conveyor is afforded by a plurality of supporting plates 24, each of which is of a size to receive and carry a carton 25, one end of which it is desired to seal during the interval of its passage in front of the wax containing reservoir.

In order to tip the conveyor to the desired degree, any suitable form of appliance may be provided, as, for instance, a roller 26 mounted upon the end of a swinging arm 27 pivoted at 28 to a standard 29, the heel

30 of which may be vertically adjusted by means of a screw 31 or like device. By adjusting the screw, the chain conveyor may be slightly twisted or canted to afford the desired obliquity in its surface to bring the end of the carton into proper relation to the sealing column or sheet of falling wax.

The falling column of wax, which is indicated by A, is discharged through an orifice 10 located between the upper edge of a weir 32 and a slide plate 33. The width of this orifice can be regulated by adjustment of the 15 slide plate, and the edge of the weir may be varied in shape, as indicated in Figs. 4 and 5. In Fig. 4 is shown an arrangement in which each end of the discharge orifice is enlarged vertically by providing notches 34 and 35, respectively, in the weir and the adjacent portion of the slide plate. In Fig. 5 20 modification consists in providing intermediate notches 36 in the edge of the weir in conjunction with complementary V-shaped teeth 37 in the edge of the slide plate which, in effect, divides the discharge orifice into three 25 sections, which will result in practically dividing the outflowing column of melted wax into three sheets or columns.

It has been shown by demonstration that an outflowing stream or sheet of melted wax 30 of the character used for sealing purposes will tend by reason of its viscosity and by its accelerating rate of flow as it falls to draw together or narrow as it elongates without, however, breaking into individual drops 35 or particles, and this convergence or narrowing of the falling column is accompanied by the formation along each of the edges of the lips a in which the column is thickened in comparison with the thickness of the intermediate sheet between the lips. This tendency to thicken at the edges may be accentuated by giving to the discharge orifice the configuration shown in Fig. 4, in which the 40 ends of the orifice are enlarged to permit of an increased discharge at the margins of the falling sheet.

If, however, it is desired to divide the column into a plurality of sections, so that each section in turn will present a pair of thickened marginal edges, the configuration shown in Fig. 5 may be employed. In either event, the formation of the thickened marginal edges is taken advantage of in the end sealing operation of the cartons by reason of 50 the fact that the ends which require sealing are passed through at an angle to the normal plane of the falling column, and hence serve to restrict or hold back the column within the space afforded between the front surface 55 of the weir plate 38 and the end wall of the carton 25^a, so that the falling column, instead of traversing the plane indicated by the dotted line b in Fig. 2, will be crowded back somewhat and thus held in close sealing contact with the end face of the carton.

At the same time, the passage of the advancing edge of the carton through the thickened marginal lip of the falling column will serve to seal the edge of the carton around onto the side face to a slight degree, thereby 70 completely sealing this advancing edge around the corner. In like manner, the rear edge of a carton, as it passes beyond the lip of the falling column, will allow the wax to flow in behind the rear edge and seal around 75 the rear corner to the degree required to secure a complete seal.

The wax will seal over and around the upper edge at the point c by reason of the fact that the restriction of the normal outflow of the wax, due to the traversing of the carton, will cause an outflowing of the wax over the upper corner which will thoroughly seal the carton at this point. The lower corner will be sealed by the provision 80 of a shelf or ledge 39 which is adjustably mounted upon the weir wall 38, being provided with slotted ears 40 through which are entered screws 41 permitting vertical 85 adjustment of the ledge. As the downward- 90 flowing wax strikes against the ledge, it will be diverted outwardly and under the edge of the carton sealing around the lower corner as indicated in Fig. 2.

As before stated, the carton is preferably 95 held in oblique relation by tipping or tilting the conveyor, and this is done for the purpose of bringing the end of the carton almost into parallelism with the normal plane of flow of the wax, which tends, as it falls, 100 to diverge outwardly away from a vertical falling position due to the maintenance of a head of wax above the weir outlet, as indicated in Fig. 2. It is highly desirable to provide for precise adjustment not only of the carton, but also of the appliance for 105 regulating the discharge of the wax, and the means for securing such adjustment will now be described.

The weir plate 38 constitutes the front 110 wall of a box-like frame 42 of rectangular shape comprising a lower wall 43, side walls 44 and a top wall 45, the side walls being provided with grooves 46 which afford guides for the vertical adjustment of the slide plate 115 33. The frame 43, which may be referred to as the outer frame, is telescopically guided within an intermediate frame 47 comprising a wall 48 having a depending flange 49, which wall merges into side walls 49^a connected with a top wall 50. The intermediate frame is also provided with side flanges 51, the upper ends of which are carried upwardly in the form of upstanding bracket arms 52, each rearwardly turned at its upper 120 end 53 to receive an adjusting screw 54.

The adjusting screws are threaded onto the upper edge of a gate 55, which gate comprises segmental side walls 56 and an arcuate bottom wall 57. The gate is pivoted 130

on trunnions 59 extending into a fixed frame 60 which is mounted upon the front wall 12 of the reservoir, and the frame furnishes a margin for an orifice 61 of proper dimensions 5 to permit the gate to be swung in and out upon the trunnions 59 without permitting discharge of the wax around the margins of the gate frame.

In addition to the screw 54, which permit 10 regulation of the height of the intermediate frame, the side flanges 51 of the latter are provided with slots 62 through which are entered screw posts 63 carrying nuts 64 for clamping the intermediate frame in adjusted 15 position upon the gate, and this adjustment serves to regulate the vertical height of the overflow edge of the weir 32 and to hold the intermediate frame with the parts carried thereby in closely abutting relation to the 20 forward edge of the gate to prevent the escape of wax at this point. The side walls of the intermediate frame are provided with outstanding lugs 65 which receive the ends of adjusting screws 66 threaded through lugs 25 67 on the outer frame, and by adjustment of said screws, the outer frame can be regulated to vary its distance toward or from the conveyer which enables adjustment to be made with respect to the width of the cartons to 30 be sealed.

The obliquity of the weir wall 38 may be regulated by swinging the gate on its trunnion through the desired degree, so that by suitable adjustment, the relation of the parts 35 may be varied to bring the weir wall 38 from a substantially vertical plane to a sharp degree of obliquity, as occasion may require. The swinging adjustment of the gate will be regulated by means of a screw 68 40 which extends through a lug or ear 69 on the edge of the gate wall 55. The end of the screw bears against the outer wall of the tank, so that by turning the screw, the gate and all of the parts carried thereby may 45 be swung as a unit to secure the desired adjustment.

In order to bring the inner ends of the cartons into proper relation to the discharge of wax from the weir, an adjustable shoe 70 50 is provided having an elongated slot 71 which is guided by a pin 72 outstanding from the side wall 49 of the intermediate wall, which pin in conjunction with a screw 73 serves to regulate the degree of projection 55 of the shoe beyond the face of the weir wall 38.

The general arrangement of the sealing appliance is diagrammatically illustrated in Fig. 3. In this figure, it will be noted that 60 one pair of tanks is located on the right hand side of the conveyor and at one point in the line of travel, and that a second pair is located on the opposite side at a different point from the line of travel. The first tank of each pair is employed to contain the wax

or similar sealing composition, and the companion tank is employed for the discharge of cold water, which is desirable where an immediate chilling of the wax is required in order to afford a smooth surface to the 70 seal coating.

The discharge of the water upon the freshly applied wax will instantly hold the same and will give a better finish than would otherwise be obtained. The previously unsealed end of the carton will be sealed by a second operation at a point through and along in the line of travel, the conveyor being oppositely tilted to bring the guides into proper relation to the second set of sealing appliances. Each of the tanks is preferably constructed in the manner heretofore described, although obviously the water tank may be omitted where it is not desired to secure the chilling effect.

The cartons to be sealed will usually be wrapped in an oiled or waxed water proof paper which affords the required amount of sealing for the body of the carton, so that an application of wax in the manner described need be made only at the ends of the carton to cover over, hold down, and seal the folds of the wrapping at the ends and around the end edges, the ends ordinarily being glued or otherwise fastened 95 before being wax sealed.

The operation of the device may be briefly summarized as follows:

The hot melted wax or like composition will be discharged into the reservoir until 100 it reaches the overflow point, which may be adjusted to secure the desired head of wax above the weir level by adjustment of the overflow cap 19 in the manner described. The vertical elevation of the weir edge 32 105 may be effected by adjusting the intermediate frame up and down across the face of the gate by turning the adjusting screws 54.

A proper lateral adjustment of the weir edge with respect to the conveyor may be 110 effected by moving the outer frame in or out of the intermediate frame by adjustment of the screw 66 until the desired relation of these parts is obtained. The angularity or obliquity of the weir wall may be adjusted 115 by a swinging adjustment of the segmental gate which carries with it the intermediate outer frames and parts associated therewith. The width of the discharge slot or orifice above the weir may be regulated by the slide plate 33 and the proper tilt of the conveyor may be regulated by the screw 31 or other equivalent appliances. Finally, the ledge 39 may be adjusted to afford the necessary 120 space for the discharge of wax under the lower edge of the carton, and the shoe 70 may be adjusted to regulate the distance of the carton from the weir opening.

When all of the adjustments have been 125 properly effected, the wax will discharge 130

through the weir opening in a sheet or column having the lipped configuration previously described, and as the cartons pass in succession through the discharging sheet or 5 column of wax, the end faces will be coated with wax, which coating will extend slightly around each of the edges, so that a complete seal at one end will be provided for. The melted wax should be discharged in the 10 tank at a proper rate of flow to maintain the desired level, and with the level properly maintained, a uniform sealing effect will be produced on all of the cartons delivered in a continuously traveling process- 15 sion as the conveyor advances.

Where the water tanks are used for chilling purposes, the water discharge will be regulated in the same manner by adjustment of the various portions of the water dis- 20 charging apparatus, and thereafter the cartons in a continuously moving procession will be brought into the proper relation with the second set of sealing and chilling appliances, which will seal the opposite ends of 25 the cartons prior to their ultimate delivery. By providing the adjustments indicated, and by employing a weir discharge configured, if desired, to increase the thickness of the lips along the margins of the falling sheet 30 or column of wax, precision in the application of the wax to the ends and edges of the margins may be obtained and uniformity in the sealing effect secured.

The apparatus as a whole is one which 35 may be readily applied to conveyors of existing type without in any way interfering with the speed or continuity of travel of the cartons from the wrapping machine to the point of delivery.

40 Although the apparatus has been described with considerable detail, and although provision has been made for all of the desirable adjustments which might be required to secure precision of operation under diverse 45 conditions, it is not the intention in the claims, unless otherwise indicated, to limit the invention to all of the details indicated.

I claim:

1. In sealing apparatus of the character 50 described, in combination with a conveyor, a tank for containing a sealing medium in the liquid state, said tank having a weir located in adjacent relation to the conveyor and in position to discharge a sheet of liquid 55 sealing medium against the surface of objects carried by the conveyor, and means for adjusting the height of the weir opening with respect to the conveyor, substantially as described.

60 2. In sealing apparatus of the character described, in combination with a conveyor, a tank for containing a sealing medium in the liquid state, said tank having a weir located in adjacent relation to the conveyor 65 and in position to discharge a sheet of liquid

sealing medium against the surface of objects carried by the conveyor, means for adjusting the height of the weir opening with respect to the conveyor, and means for adjusting the angular relation of the weir to the conveyor, substantially as described. 70

3. In sealing apparatus of the character described, in combination with a conveyor, a tank for containing a sealing medium in the liquid state, said tank having a weir located in adjacent relation to the conveyor and in position to discharge a sheet of liquid sealing medium against the surface of objects carried by the conveyor, means for adjusting the height of the weir opening with respect to the conveyor, means for adjusting the angular relation of the weir to the conveyor, and means for adjusting the weir opening toward and from the conveyor, substantially as described. 75 80

4. In sealing apparatus of the character described, in combination with a conveyor, a tank for containing a sealing medium in the liquid state, said tank having a weir located in adjacent relation to the conveyor and in position to discharge a sheet of liquid sealing medium against the surface of objects carried by the conveyor, and means for adjusting the width of the weir opening, substantially as described. 85 90

5. In sealing apparatus of the character described, in combination with a conveyor, a tank for containing a sealing medium in the liquid state, said tank having a weir located in adjacent relation to the conveyor and in position to discharge a sheet of liquid sealing medium against the surface of objects carried by the conveyor, means for adjusting the height of the weir opening with respect to the conveyor, and means for adjusting the width of the weir opening, substantially as described. 95 100

6. In sealing apparatus of the character described, in combination with a conveyor, a tank for containing a sealing medium in the liquid state, said tank having a weir located in adjacent relation to the conveyor and in position to discharge a sheet of liquid sealing medium against the surface of objects carried by the conveyor, means for adjusting the height of the weir opening with respect to the conveyor, means for adjusting the angular relation of the weir to the conveyor, and means for adjusting the width of the weir opening, substantially as described. 105 110 115

7. In sealing apparatus of the character described, in combination with a conveyor, a tank for containing a sealing medium in the liquid state, said tank having a weir located in adjacent relation to the conveyor and in position to discharge a sheet of liquid sealing medium against the surface of objects carried by the conveyor, means for adjusting the height of the weir opening with 120 125 130

- respect to the conveyor, means for adjusting the angular relation to the weir to the conveyor, means for adjusting the weir opening toward and from the conveyor, and means for adjusting the width of the weir opening, substantially as described.
8. In sealing apparatus of the character described, in combination with a conveyor, a tank for containing a sealing medium in the liquid state, said tank having a weir located in adjacent relation to the conveyor and in position to discharge a sheet of liquid sealing medium against the surface of objects carried by the conveyor, and means for adjusting the weir opening toward and from the conveyor, substantially as described.
9. In sealing apparatus of the character described, in combination with a conveyor, a tank for containing a sealing medium in the liquid state, said tank having a weir located in adjacent relation to the conveyor and in position to discharge a sheet of liquid sealing medium against the surface of objects carried by the conveyor, and means for adjusting the weir toward and from the conveyor, and means for adjusting the angularity of the weir with respect to the conveyor, substantially as described.
10. In sealing apparatus of the character described, in combination with a conveyor, a tank for containing a sealing medium in the liquid state, said tank having a weir located in adjacent relation to the conveyor and in position to discharge a sheet of liquid sealing medium against the surface of objects carried by the conveyor, and means for adjusting the weir toward and from the conveyor, and means for varying the weir opening, substantially as described.
11. In sealing apparatus of the character described, in combination with a conveyor, a tank for containing a sealing medium in the liquid state, said tank having a weir located in adjacent relation to the conveyor and in position to discharge a sheet of liquid sealing medium against the surface of objects carried by the conveyor, and means for adjusting the angularity of the weir with respect to the conveyor, and means for varying the width of the weir opening, substantially as described.
12. In combination with a continuously moving conveyor and means for tilting the conveyor, a tank for the storing of a liquid sealing medium located in laterally adjacent relation to the conveyor, said tank being provided with a weir adapted to discharge a sheet of liquid sealing medium against the surface of objects carried by the conveyor, substantially as described.
13. In combination with a continuously moving conveyor and means for tilting the conveyor, a tank for the storing of a liquid sealing medium located in laterally adjacent relation to the conveyor, said tank being provided with a weir adapted to discharge a sheet of liquid sealing medium against the surface of objects carried by the conveyor, and means for adjusting the relation of the weir opening with respect to the conveyor, substantially as described.
14. In combination with a continuously moving conveyor and means for tilting the conveyor, a tank for the storing of a liquid sealing medium located in laterally adjacent relation to the conveyor, said tank being provided with a weir adapted to discharge a sheet of liquid sealing medium against the surface of objects carried by the conveyor, means for adjusting the relation of the weir opening with respect to the conveyor, and means for adjusting the size of the weir opening, substantially as described.
15. In sealing apparatus of the class described, the combination of a tilttable conveyor, a tank for the reception of a liquid sealing medium in laterally adjacent relation to the conveyor, said tank being provided with a swinging gate comprising segmental side walls and an arcuate end wall, said gate carrying an intermediate frame vertically adjustable with respect to the gate, said intermediate frame carrying an outer frame adjustable in and out of the intermediate frame, said outer frame being configured to afford a weir opening for the discharge of sealing medium against the face of objects carried by the conveyor, and a slide plate carried by the outer frame and co-acting with the edge of the weir for regulating the width of the discharge over the weir, substantially as described.
16. In sealing apparatus of the class described, the combination of a tilttable conveyor, a tank for the reception of a liquid sealing medium in laterally adjacent relation to the conveyor, said tank being provided with a swinging gate comprising segmental side walls and an arcuate end wall, said gate carrying an intermediate frame vertically adjustable with respect to the gate, said intermediate frame carrying an outer frame adjustable in and out of the intermediate frame, said outer frame being configured to afford a weir opening for the discharge of sealing medium against the face of objects carried by the conveyor, a slide plate carried by the outer frame and co-acting with the edge of the weir for regulating the width of the discharge over the weir, and a ledge on the outer frame located below the weir opening for diverting the falling sheet of sealing medium under the lower edge of the object to be sealed, substantially as described.
17. In sealing apparatus of the class described, the combination of a tilttable conveyor, a tank for the reception of a liquid sealing medium in laterally adjacent relation to the conveyor, said tank being provided with a swinging gate comprising segmental side walls and an arcuate end wall, said gate carrying an intermediate frame vertically adjustable with respect to the gate, said intermediate frame carrying an outer frame adjustable in and out of the intermediate frame, said outer frame being configured to afford a weir opening for the discharge of sealing medium against the face of objects carried by the conveyor, a slide plate carried by the outer frame and co-acting with the edge of the weir for regulating the width of the discharge over the weir, and a ledge on the outer frame located below the weir opening for diverting the falling sheet of sealing medium under the lower edge of the object to be sealed, substantially as described.

- tion to the conveyor, said tank being provided with a swinging gate comprising segmental side walls and an arcuate end wall, said gate carrying an intermediate frame 5 vertically adjustable with respect to the gate, said intermediate frame carrying an outer frame adjustable in and out of the intermediate frame, said outer frame being configured to afford a weir opening for the 10 discharge of sealing medium against the face of objects carried by the conveyor, a slide plate carried by the outer frame and co-acting with the edge of the weir for regulating the width of the discharge over the 15 weir, a ledge on the outer frame located below the weir opening for diverting the falling sheet of sealing medium under the lower edge of the object to be sealed, and an adjustable shoe for regulating the position 20 of the to-be-sealed object with respect to the discharge from the weir, substantially as described.
18. In sealing apparatus of the class described, the combination of a tilttable conveyor, a tank for the reception of a liquid sealing medium in laterally adjacent relation to the conveyor, said tank being provided with a swinging gate comprising segmental side walls and an arcuate end wall, 25 said gate carrying an intermediate frame vertically adjustable with respect to the gate, said intermediate frame carrying an outer frame adjustable in and out of the intermediate frame, said outer frame being configured to afford a weir opening for the 30 discharge of sealing medium against the face of objects carried by the conveyor, a slide plate carried by the outer frame and co-acting with the edge of the weir for regulating the width of the discharge over the 35 weir, and a drain pan located below the line of discharge from the weir for intercepting the surplus sealing medium, substantially as described.
19. In sealing apparatus of the class described, the combination of a tilttable conveyor, a tank for the reception of a liquid sealing medium in laterally adjacent relation to the conveyor, said tank being provided with a swinging gate comprising seg- 40
- mental side walls and an arcuate end wall, said gate carrying an intermediate frame vertically adjustable with respect to the gate, said intermediate frame carrying an outer frame adjustable in and out of the intermediate frame, said outer frame being configured to afford a weir opening for the discharge of sealing medium against the face of objects carried by the conveyor, a slide plate carried by the outer frame and co-acting with the edge of the weir for regulating the width of the discharge over the weir, a ledge on the outer frame located below the weir opening for diverting the falling sheet of sealing medium under the lower edge of the object to be sealed, and a drain pan located below the line of discharge from the weir for intercepting the surplus sealing medium, substantially as described. 45
20. In sealing apparatus of the class described, the combination of a tilttable conveyor, a tank for the reception of a liquid sealing medium in laterally adjacent relation to the conveyor, said tank being provided with a swinging gate comprising segmental side walls and an arcuate end wall, 50 said gate carrying an intermediate frame vertically adjustable with respect to the gate, said intermediate frame carrying an outer frame adjustable in and out of the intermediate frame, said outer frame being configured to afford a weir opening for the discharge of sealing medium against the face of objects carried by the conveyor, a slide plate carried by the outer frame and co-acting with the edge of the weir for regulating the width of the discharge over the weir, a ledge on the outer frame located below the weir opening for diverting the falling sheet of sealing medium under the lower edge of the object to be sealed, an adjustable shoe for regulating the position of the to-be-sealed object with respect to the discharge from the weir, and a drain pan located below the line of discharge from the weir for intercepting the surplus sealing medium, substantially as described. 55
